**HATCH COVER AND CONNING TOWER
MECHANISM**

Franklin E. Rigsby and Woodrow Rigsby, both of
9525 Fritz Road, Fort Wayne, Ind.
Filed July 16, 1964, Ser. No. 383,042
9 Claims. (Cl. 114—16)

The present invention relates generally to a submarine hatch cover and conning tower mechanism, and more specifically to a relatively simple and inexpensive hatch cover and conning tower mechanism especially adapted to a relatively small-sized submarine such as that demanded by the aquatic sportsman.

Submarines have been known to the public for many years. Each submarine that has been developed during this period of time has a hatch, a watertight hatch cover, and a conning tower as an essential part. The hatch allows ingress and egress of the submarine crew, and any supplies or cargo carried aboard the submarine. As every submarine is submersible, a hatch cover must be provided to close the hatch thereby to prevent water from seeping into the hull whenever the submarine is submerged. Still further, as all submarines lie relatively low in the water when surfaced, it is imperative that a hatch elevated by means of a conning tower be provided whenever the hatch is open to prevent water from entering the hull through the open hatch. While various hatch cover mechanisms and conning towers have been suggested, they have been relatively expensive to manufacture or unduly intricate, have caused an excessive amount of hydrodynamic drag and thereby requiring propulsion systems that are larger than necessary, or have been otherwise unsuitable for use on a relatively small submarine. It is therefore desirable to provide a simple and relatively inexpensive hatch cover and conning tower mechanism for a relatively small submarine that produces a minimal hydrodynamic drag whenever the hull is submerged.

Accordingly, an object of this invention is to provide an improved hatch cover and conning tower mechanism especially adapted to a relatively small submarine.

Another object of this invention is to provide an improved hatch cover mechanism which is relatively inexpensive to manufacture.

Another object of this invention is to provide an improved conning tower mechanism which minimizes the hydrodynamic drag on the hull when it is submerged.

It is a further object of this invention to provide an inexpensive hatch cover and conning tower mechanism especially adaptable to a relatively small submarine and which minimizes the hydrodynamic drag on the hull whenever it is submerged.

In the broader aspects of this invention, there is provided a submarine hull having a hatch and a hatch cover. On either side of the hatch there are a pair of hatch-supporting arms pivotally secured to the hull at one end and to the hatch cover at the opposite end, the hatch cover being movable from a hatch-closing position to a hatch-opening position. Secured within the hatch is an extensible conning tower having a transparent shield which is movable to a fully extended position when the hatch cover is in the hatch-opening position and to a collapsed position within the hatch when the hatch cover is in the hatch-closing position. The hatch cover prevents water from entering the hull when the hatch is closed, and the conning tower fully surrounds the hatch thereby preventing water from entering the hatch when the hatch cover is in the hatch-opening position when the hull is surfaced.

The above-mentioned and other features and objects

2

of this invention and the manner of attaining them will become more apparent and the invention itself will be best understood by reference to the following description of an embodiment of the invention taken in conjunction with the accompanying drawings, wherein:

FIG. 1 is a fragmentary top view of the hatch cover mechanism of this invention;

FIG. 2 is a fragmentary side view of the hatch cover and conning tower mechanism of this invention showing the conning tower in its fully extended position, the hatch cover in its hatch-opening position, and the adjustable seat mounted within the submarine hull in registry with the hatch;

FIG. 3 is a fragmentary side view, in cross-section, showing the hatch cover in hatch-closing position, conning tower in its collapsed position, and the resilient lock means engaged to the handles within the hatch cover;

FIG. 4 is a fragmentary top view, partially in cross-section, showing the hatch cover in hatch-closing position and the conning tower in its collapsed position;

FIG. 5 is a fragmentary rear view, partially in cross-section, showing the hatch cover in its hatch-opening position, and the conning tower in its fully extended position; and

FIG. 6 is a fragmentary perspective view of the hatch cover shown in its hatch-closing position.

Referring to the drawings, there is illustrated a submarine hatch cover and conning tower mechanism generally comprising a submarine hull 10, a hatch 12, a hatch cover 14, an extensible conning tower 16, and a seat mechanism 18 which is adjustable in height.

The hatch 12 is shown to be generally circular and having an upwardly facing peripheral seat 20 which lies in a plane which intersects a straight line 22 which also intersects the longitudinal axis 24 of the hull 10 and is perpendicular to both the plane and the axis 24.

The hatch cover 14 comprises a base member 26 and a dome 28. Base member 26 has a pair of opposite and coaxial circular end openings 30, 32. End opening 30 is substantially the same size as hatch 12 and larger in diameter than end opening 32. Base member 26 has a peripheral seat 34 surrounding end opening 30 which has a peripheral groove 36 therein. Secured in peripheral groove 36 is a conventional rubber O-ring 38 for sealing the hatch cover 14 to the hatch 12. Seat 34 has a size which corresponds to seat 20 and can be mated with seat 20 in sealing relationship with O-ring 38 compressed therebetween. Dome 28 comprises a transparent and cylindrical tube 40 having opposite open ends 42, 44 and a transparent end plate 46. End plate 46 is secured to end 42 of tube 40 thereby closing end 42. End plate 46 and tube 40 are preferably made of Plexiglas or some other transparent, self-supporting, and strong material. In the specific embodiment illustrated, the plate 46 is secured to tube 40 by a suitable adhesive or solvent; however, any means by which end plate 46 can be secured to end 42 of tube 40 in a manner that is strong and impervious to moisture would be satisfactory. End plate 46 is provided with a thickness which is substantially greater than the wall thickness of tube 40 thereby to provide the end plate 46 with a strength equal to the walls of tube 40. Dome 28 is coaxially secured to base member 26 with the open end 44 in registry with the end opening 32.

A gasket (not shown) is provided and placed between the dome 28 and the base member 26. The end opening 32 and the interior diameter of the dome 28 are substantially equal so that when the dome 28 is properly installed on the base member 26, the gasket is compressed between the end 44 of the dome 28 and the portion of the base member 26 surrounding and adjacent the opening 32.

Dome 28 is coaxially secured to base member 26 with the open end 44 in registry with the end opening 32. A gasket (not shown) is provided and placed between the dome 28 and the base member 26. The end opening 32 and the interior diameter of the dome 28 are substantially equal so that when the dome 28 is properly installed on the base member 26, the gasket is compressed between the end 44 of the dome 28 and the portion of the base member 26 surrounding and adjacent the opening 32.

Dome 28 is coaxially secured to base member 26 with the open end 44 in registry with the end opening 32. A gasket (not shown) is provided and placed between the dome 28 and the base member 26. The end opening 32 and the interior diameter of the dome 28 are substantially equal so that when the dome 28 is properly installed on the base member 26, the gasket is compressed between the end 44 of the dome 28 and the portion of the base member 26 surrounding and adjacent the opening 32.

Dome 28 is coaxially secured to base member 26 with the open end 44 in registry with the end opening 32. A gasket (not shown) is provided and placed between the dome 28 and the base member 26. The end opening 32 and the interior diameter of the dome 28 are substantially equal so that when the dome 28 is properly installed on the base member 26, the gasket is compressed between the end 44 of the dome 28 and the portion of the base member 26 surrounding and adjacent the opening 32.

Dome 28 is coaxially secured to base member 26 with the open end 44 in registry with the end opening 32. A gasket (not shown) is provided and placed between the dome 28 and the base member 26. The end opening 32 and the interior diameter of the dome 28 are substantially equal so that when the dome 28 is properly installed on the base member 26, the gasket is compressed between the end 44 of the dome 28 and the portion of the base member 26 surrounding and adjacent the opening 32.

Dome 28 is coaxially secured to base member 26 with the open end 44 in registry with the end opening 32. A gasket (not shown) is provided and placed between the dome 28 and the base member 26. The end opening 32 and the interior diameter of the dome 28 are substantially equal so that when the dome 28 is properly installed on the base member 26, the gasket is compressed between the end 44 of the dome 28 and the portion of the base member 26 surrounding and adjacent the opening 32.

Dome 28 is secured to base member 26 by means of a pair of ears 50 which are secured to the end plate 46 at diametrically opposite positions and the threaded receptacles 52 formed in the base member 26 at a position in registry with the ears 50. Bolts 54 are passed through ears 50 and are threaded into the receptacles 52 thereby securing dome 28 to the base member 26 and also providing additional security of the end plate 46 to the tube 40. Secured within hatch cover 14 and on either side of base member 26 in alignment with the longitudinal axis 24 are a pair of handles 57. Handles 57 provide a means by which the occupant of the submarine can lift the hatch cover 14 or lower the hatch cover 14 to open and close the hatch 12, respectively, and to lock the hatch cover 14 in hatch-closing position, as will be described hereinafter.

The hatch cover 14 is mounted onto hull 10 by means of a pair of hatch support arms 56 having opposite ends 58, 60 which have right and left threaded portions (not shown), respectively. Headedly received on ends 58, 60 are identical ball and socket joint mechanisms 62 thereby forming with support arms 56 a turnbuckle by which the arms 56 may be adjusted in length. Support arms 56 are secured to the hull 10 by means of a hatch support 64 which is secured to hull 10 on opposite sides of hatch 12. Specifically, the ball portions of mechanism 62 have a threaded stud portion 66 which is secured to hatch support 64 by means of a pair of conventional nuts 68 on either side of support 64. Stud portion 66 has a length such that by positioning the bolts 68 at various positions along the length of stud portion 66, the security of hatch support arms 56 is adjustable in a direction perpendicular to the longitudinal axis 24. In a similar manner, stud portion 66 of the ball and socket joint mechanism 62 at end 58 of arms 56 are secured to a pair of ears 70 secured to base member 26 on either side of dome 28. In this manner, the hatch cover 14 is swivelly secured to the hatch supporting arms 56 which are in turn swivelly secured to the submarine hull 10. The guard rod 72 is secured to the distal ends of the ball and socket joint mechanism 62 attached to end 58 of the hatch support arms 56 thereby interconnecting both of the support arms 56 and forming a yoke 74 therewith. Yoke 74 surrounds hatch cover 14 and is rotatable with respect to hull 10 about an axis 76 which is perpendicular to axis 24, and hatch cover 14 is rotatable within yoke 74 about axis 78 which is also perpendicular to axis 24 (see FIG. 1).

Hatch cover 14 mounted in the above-described manner is rotatable from a hatch-closing position in which seat 34 is mated to seat 20 with the O-ring 38 compressed therebetween, through a series of intermediate positions, to a hatch-opening position in which the hatch cover 14 is inclined to the longitudinal axis 24 of the hull 10, as shown in FIG. 2.

A pair of hatch cover guide bars is secured to hull 10 adjacent to and on opposite sides of the hatch 12 to position the hatch cover 14 in registry with the hatch 12 when the latter two parts are adjacent thereby to insure the mating of the seat 34 to the seat 20 when the hatch cover 14 is placed in the hatch-closing position. This function is performed by the hatch cover guide bars 80 by being spaced apart a distance equal to the diameter of the base member 26 at end 30 thereby rejecting the hatch cover 14 unless it is properly aligned in the direction of axis 78. Such alignment, if needed, is made as aforementioned by moving the nuts 68 along the studs 66 at either of the ends 58, 60 of the hatch cover support rods 56. The alignment of hatch cover 14 with the hatch 12 in the direction perpendicular thereto, i.e., in the direction of axis 24, is made by adjusting the length of hatch support rods 56 by means of the turnbuckle mechanism thereof, said adjustment being maintained by tightening locking nuts 82 against the ball and socket joint mechanism 62 and end 58 of the hatch cover support arms 56.

A pair of resilient straps 84 are secured within hatch

12 to opposite sides of the hull 10. Straps 84 are engageable with the handles 57 when the hatch cover 14 is in the hatch-closing position as shown in FIG. 1. The straps 84 are slid onto the handles 57 and provide a locking means for the hatch cover 14. Straps 84 also provide an additional force between the seats 34, 20 that aids in the compression of O-ring 38 therebetween. While it has been found in some embodiments of this invention that water seeps under the hatch cover 14 when the submarine is submerged near the surface where no water pressure is available to help seal the hatch cover 14, this additional compressive force on the O-ring 38 provided by the straps 84 has been found to alleviate this difficulty.

A hook 86 is secured to the hull 10 at a position axially displaced from the hatch 12 and a resilient strip 88 is secured to the hull 10 therebetween. A detent 90 is formed on the base member 26 adjacent the peripheral portion of the base member 26 upon which the hatch cover 14 rests when the hatch cover 14 is in the hatch-opening position as shown in FIG. 2. Detent 90 engages the hook 86 and the aforesaid peripheral portion of the base member 26 engages the resilient strip 88 when the hatch cover 14 is in the aforementioned hatch-opening position. The combination of the frictional forces between the hatch cover 14 and the resilient strip 88 and the detent 90 and the hook 86, respectively, holds the hatch cover in the hatch-opening position. It has been found that the hatch cover 14 secured in the hatch-opening position by the aforesaid means is stable under all conditions of rough water.

Referring now specifically to FIG. 2, a seat 18 which is adjustable in height will now be described. Seat 18 is mounted onto the hull 10 by means of two pair of seat supports 92 which are secured to the interior of the hull 10 opposite each other. Supports 92 define a rectangle having a support 92 at each corner thereof and lying in a plane parallel to the plane of the peripheral seat 20 aforementioned and being in registry with the hatch 12. Each pair of supports 92 secures a rod 94 to the hull 10. Secured between rods 94 is a strip 96 of seat fabric having opposite ends. One end of the strip 96 is secured to one of the rods 94 which is immovably secured to the seat supports 92. The other end of the strip 96 is secured to the rod 94 (shown in FIG. 2) which is removably secured in the supports 92 thereby providing that the strip 96 can be rolled on the second-mentioned rod 94 as shown and secured when desired. This feature provides adjustment in the height of the strip 96 by merely adjusting the slack in the same. Removable security of the second-mentioned rod 94 is achieved by means of a tongue portion 98 of the rod 94 which fits into a slot 100 in one of the seat supports 92 (shown in FIG. 2).

Referring now specifically to FIGS. 2 through 4, there is shown an extensible conning tower 16 which is movable to a fully-extended position when hatch cover 14 is in hatch-opening position (see FIG. 2) and to a fully collapsed position within hatch 12 when the hatch cover is in the hatch-closing position (see FIG. 3). Conning tower 16 generally comprises a strip 102 of flexible and transparent material which can be any material which is impervious to moisture and has the combined properties of the required strength, the required optical properties, and does not become cloudy or brittle with age. 12-gauge polystyrene sheet material has proven satisfactory; however, such other materials such as those used to make flexible convertible top windows or transparent automobile seat covers could also be used. Flexible strip 102 is joined at its ends thereby forming a tube. Secured to the longitudinal edges of the strip 102 (opposite ends of the tube) are a pair of self-supporting, metal rings 104 and 106. Ring 104 is preferably made of metal and has a diameter such that it can pass through ring 106. Ring 106 must have both strength and resiliency; and, therefore, is preferably made with a metal core 108 and a resilient rubber surface coating 110. Ring 106 has a diameter such that it will snugly fit within hatch 12. The ring 106 is secured

within hatch 12 and adjacent and parallel seat 20 with a portion of the strip 102 between the ring 106 and the hatch 12. The securance of ring 106 is achieved by means of a plurality of clamps 112 which urge the ring 106 against the hatch 12 compressing the resilient surface therebetween and circumferentially sealing the ring 106 and the strip 102 to the hatch 12. By means of this securance, when the conning tower 16 is extended, as shown in FIG. 5, the conning tower prevents waves from breaking over the hatch 12 and entering the hull 10. Further, the conning tower 16 in its collapsed position within hatch 12, as shown in FIG. 3, collects whatever seepage there may be between the hatch cover 14 and the hatch 12 in the fold 114 preventing such seepage from wetting the occupants of the submarine and permitting easy bailing of such seepage when the submarine is surfaced by merely opening the hatch cover 14 and extending the conning tower into position of FIG. 5.

A pair of conning tower supports 116 are secured to hull 10 and extend above the hatch 12 on opposite sides thereof. In the embodiment shown in the drawings, conning tower supports 116 are strengthened by means of a pair of bracket portions 118. A pair of spring elements 120 are provided to hold the conning tower 16 in its fully-extended position. Springs 120 have opposite ends 122 and 124. End 122 is secured to ring 104 at diametrically opposed positions and ends 124 are engageable to the conning tower supports 116 whenever the conning tower 16 is fully extended as shown in FIGS. 2 and 5.

In a specific embodiment, those elements of the present invention which have not been heretofore described as being preferably made out of any specific material can be made of any suitably strong metal. Steel is preferred as it is relatively inexpensive. Further, securance of all previously-mentioned metal parts to other metal parts is preferably done by welding, brazing or the like means; however, the use of conventional nuts and bolts, rivets, and the like may be used so long as such securing means are sealed so as to prevent water seepage.

In operation, the hatch cover and conning tower mechanism of this invention is used on a relatively small submarine to prevent water from entering the hull 10 through the hatch 12 both when the submarine is submerged and when the submarine is surfaced. When the submarine is surfaced, the conning tower 16 is extended in the position shown in FIG. 2, thereby preventing waves from breaking over the peripheral seat 20 and into the hatch 12. As soon as the crew of the submarine enters, the submarine is prepared for submergence by collapsing the conning tower 16 and closing the hatch cover 14 by grasping the handles 57 and rotatably urging the hatch cover 14 onto the seat 20 of the hatch 12. When the hatch cover 14 is properly closed and locked by means of the resilient strips 84 being engaged to the handles 57, the hatch cover 14 seals the hatch 12 from any seepage of water whether surfaced or submerged. Dome 28 of the hatch cover 14 is of such a size that a person's head fits comfortably therein and allows him to see therethrough in any direction he desires.

When the occupant of the submarine is properly positioned within the submarine hull 10, his head must be centrally located within the dome 28 so that he may properly see to navigate the submarine. When in the proper position, the operator may also navigate the submarine with the hatch cover 14 in the hatch-opening position of FIG. 2 and with the conning tower 16 in its fully-extended position as visibility may be had through the conning tower 16. For proper positioning of the occupant in the dome 28, the seat 18 is adjustable in height by means of disengaging the bar 94 from the slot 100 and rolling or unrolling the strip 96 of seat fabric as needed and replacing the rod 94 within the slot 100 so as to secure the seat at the height desired. Once this adjustment is made, the adjustment need not be changed, as the proper height of the occupant is attained for navigation both with

the hatch cover 14 in a hatch-closing position and in a hatch-opening position.

While there have been described above the principles of this invention in connection with specific apparatus, it is to be clearly understood that this description is made only by way of example and not as a limitation to the scope of the invention.

What is claimed is:

1. A submarine hatch cover and conning tower mechanism comprising a submarine hull with a hatch therein having a first upwardly facing peripheral seat lying in a plane intersecting a straight line which also intersects the longitudinal axis of said hull and is perpendicular to both said plane and said axis, a hatch cover comprising a base member and a dome, said base member having a pair of opposite and coaxial, circular end openings, one of said end openings being larger than the other of said end openings and having a second peripheral seat of a size corresponding to said first peripheral seat, a peripheral groove in said second seat and an O-ring in said groove, said dome comprising a transparent cylindrical tube having opposite and open tube ends and a transparent end plate, said end plate closing one of said tube ends and having a thickness greater than the wall thickness of said tube, said dome being coaxially secured to said base with the other of said tube ends in registry with the smaller end opening of said base, said smaller end opening having diametral dimensions equal with the interior of said tube, a pair of handles secured within said hatch cover on either side of said base member in alignment with said longitudinal axis of said hull, a pair of hatch supports secured to said hull on opposite sides of said hatch equally spaced from said longitudinal axis, a pair of hatch support arms having opposite ends, a ball and socket joint mechanism at each of said ends and a turnbuckle therebetween, one of said ends being swivelly secured to said hatch supports, the other of said ends being swivelly secured to said hatch cover, the securance of at least one of said ends being adjustable in position in a direction perpendicular to said longitudinal axis, said hatch support arms being adjustable in length, a guard rod being secured to said other ends of said hatch support arms interconnecting said hatch support arms and thereby forming a yoke surrounding said hatch cover and in which said hatch cover is rotatable, said hatch cover and said yoke being movable from a hatch-closing position in which said first and second seats are mated with said O-ring compressed therebetween, through a series of intermediate positions, to a hatch-opening position in which said hatch cover is inclined to said longitudinal axis of said hull, a pair of hatch cover guide bars secured to said hull adjacent and on opposite sides of said hatch, said guide bars positioning said hatch cover in registry with said hatch when the latter two parts are adjacent thereby assuring the mating of said first and second seats, a pair of resilient lock means secured within said hatch to opposite sides of said hull, said lock means being engageable with said handles when said hatch cover is in said hatch-closing position, a hook secured to said hull at a position axially displaced from said hatch and a resilient strip secured to said hull therebetween, a detent ridge secured on said base member adjacent the portion of the periphery of said base member upon which said hatch cover rests when in said hatch-opening position, said detent ridge engaging said hook and said peripheral portion of said base member engages said strip when said hatch cover is in said hatch-opening position thereby holding said hatch cover in said hatch-opening position, and an extensible conning tower which is movable to a fully-extended position when said hatch cover is in said hatch-opening position and to a collapsed position within said hatch when said hatch cover is in said hatch-closing position whereby said hatch cover in said hatch-closing position prevents water from entering said hatch when said hull is submerged and said conning tower in said fully-extended position prevents water from entering said hatch

when said hatch cover is in said hatch-opening position and said hull is surfaced.

2. The mechanism of claim 1 wherein said extensible conning tower comprises a strip of flexible and transparent waterproof material having opposite ends and longitudinal edges, a pair of rings having different diameters, said ends of said strip being secured together and said rings secured to said opposite longitudinal edges, said larger ring fitting coaxially into said hatch and having a resilient outer surface, a plurality of clamps, said clamps securing said larger ring to said hatch with said strip therebetween, said clamps compressing said resilient surface of said larger ring against said hatch into circumferential sealing engagement with said hatch, a pair of conning tower supports secured to said hull and extending above said hatch on opposite sides thereof, a pair of spring elements having opposite ends, said spring elements being secured at one of said ends to said smaller ring at diametrically opposite positions, the other end of said spring elements being engageable with said conning tower supports when said strip is in said fully-extended position and said hatch cover is in said hatch-opening position, said strip being collapsible within said hatch when said hatch cover is in said hatch-closing position.

3. The mechanism of claim 1 further comprising two pair of seat supports secured to said hull opposite each other and within said hull, said supports defining a rectangle having a support at each corner thereof which lies in a plane parallel to said plane of said first peripheral seat, said rectangle being in registry with said hatch, two rods, one of said rods secured in one of said pairs of seat supports, the other of said rods removably secured by the other of said pairs, a strip of seat fabric having opposite ends, one of said ends being secured to said one rod, the other of said ends secured to said other rod, said strip being rolled on said other rod, thereby adjusting the height of said fabric.

4. A submarine hatch cover comprising a submarine hull with a hatch therein having a first upwardly facing peripheral seat lying in a plane intersecting a straight line which also intersects the longitudinal axis of said hull and is perpendicular to both said plane and said axis, a hatch cover comprising a base member and a dome, said base member having a pair of opposite and coaxial, circular end openings, one of said end openings being larger than the other of said end openings and having a second peripheral seat of a size corresponding to said first peripheral seat, a peripheral groove in said second seat and an O-ring in said groove, said dome comprising a transparent cylindrical tube having opposite and open tube ends and a transparent end plate, said end plate closing one of said tube ends and having a thickness greater than the wall thickness of said tube, said dome being coaxially secured to said base with the other of said tube ends in registry with the smaller end opening of said base, said smaller end opening having diametral dimensions equal with the interior of said tube, a pair of handles secured within said hatch cover on either side of said base member in alignment with said longitudinal axis of said hull, a pair of hatch supports secured to said hull on opposite sides of said hatch equally spaced from said longitudinal axis, a pair of hatch support arms having opposite ends, a ball and socket joint mechanism at each of said ends and a turnbuckle therebetween, one of said ends being swivelly secured to said hatch supports, the other of said ends being swivelly secured to said hatch cover, the security of at least one of said ends being adjustable in position in a direction perpendicular to said longitudinal axis, said hatch support arms being adjustable in length, a guard rod being secured to said other ends of said hatch support arms interconnecting said hatch support arms and thereby forming a yoke surrounding said hatch cover and in which said hatch cover is rotatable, said hatch cover and said yoke being movable from a hatch-closing position in which said first and second seats are mated with said

O-ring compressed therebetween, through a series of intermediate positions, to a hatch-opening position in which said hatch cover is inclined to said longitudinal axis of said hull, a pair of hatch cover guide bars secured to said hull adjacent and on opposite sides of said hatch, said guide bars positioning said hatch cover in registry with said hatch when the latter two parts are adjacent thereby assuring the mating of said first and second seats, a pair of resilient lock means secured within said hatch to opposite sides of said hull, said lock means being engageable with said handles when said hatch cover is in said hatch-closing position, a hook secured to said hull at a position axially displaced from said hatch and a resilient strip secured to said hull therebetween, a detent ridge secured on said base member adjacent the portion of the periphery of said base member upon which said hatch cover rests when in said hatch-opening position, said detent ridge engaging said hook and said peripheral portion of said base member engages said strip when said hatch cover is in said hatch-opening position thereby holding said hatch cover in said hatch-opening position whereby said hatch cover in said hatch-closing position prevents water from entering said hatch when said hull is submerged.

5. A submarine hatch cover and conning tower mechanism comprising a submarine hull with a hatch therein having a first upwardly facing peripheral seat and a longitudinal axis, a hatch cover having a transparent dome and a second peripheral seat corresponding in size to said first peripheral seat, a pair of handles secured within said hatch cover on either side of said base member in alignment with said longitudinal axis of said hull, a pair of hatch supporting arms having opposite ends, said supporting arms being adjustable in length, one of said ends being swivelly secured to said hull on opposite sides of said hatch, said last-mentioned security being adjustable in position in a direction perpendicular to said longitudinal axis, the other of said ends being swivelly secured to said hatch cover, a guard rod being secured to said other ends of said hatch support arms interconnecting said hatch support arms and thereby forming a yoke surrounding said hatch cover and in which said hatch cover is rotatable, said hatch cover and said yoke being movable from a hatch-closing position in which said first and second seats are mated, through a series of intermediate positions, to a hatch-opening position in which said hatch cover is inclined to said longitudinal axis of said hull, a pair of resilient lock means secured within said hatch to opposite sides of said hull, said lock means being engageable with said handles when said hatch cover is in said hatch-closing position, and an extensible conning tower which is movable to a fully-extended position when said hatch cover is in said hatch-opening position and to a collapsed position when said hatch cover is in said hatch-closing position, whereby said hatch cover in said hatch-closing position prevents water from entering said hatch when said hull is submerged and said conning tower in said fully-extended position prevents water from entering said hatch when said hatch cover is in said hatch-opening position and said hull is surfaced.

6. The mechanism of claim 5 wherein said extensible conning tower comprises a transparent, waterproof and tubular shield surrounding and coaxial to said hatch and having opposite open ends, one of said ends of said shield being peripherally secured and sealed within said hatch, a pair of conning tower supports secured to said hull and extending above said hatch on opposite sides thereof, the other of said ends of said shield being securable to said supports when said conning tower is in said fully-extended position.

7. A submarine hatch cover and conning tower comprising a submarine hull with a hatch therein, a hatch cover and a pair of hatch supporting arms having opposite ends, said hatch cover pivotally secured to said arms at one of said ends, said arms being pivotally secured to said hull on opposite sides of said hatch, said

hatch cover being movable from a hatch-closing position to a hatch-opening position, and an extensible conning tower including a transparent, waterproof and tubular shield surrounding said hatch, said shield having opposite ends, a shield end being peripherally secured and sealed to said hatch, said conning tower being movable to a fully-extended position when said hatch cover is in said hatch-opening position and to a collapsed position when said hatch cover is in said hatch-closing position, said conning tower in said fully-extended position extending above said hatch and in collapsed position being no higher than said hatch, whereby said hatch cover in said hatch-closing position prevents water from entering said hatch when said hull is submerged and said conning tower in said fully-extended position prevents water from entering said hatch when said hatch cover is in said hatch-opening position and said hull is surfaced.

8. For use in a submarine, a hull having an opening therein, a conning tower of flexible, foldable and waterproof sheet-like material, one end of said tower being positioned in registry with said opening, means sealing said one end to said hull, said tower being selectively extensible outwardly from said hull and foldable to a collapsed position within said opening, said hull in the region immediately beneath said tower being open for occu-

pancy by an operator, said tower being disposed outside said region in both collapsed and extended conditions.

9. For use in a submarine, a hull having an opening therein, a conning tower of flexible, foldable and waterproof material, one end of said tower being positioned in registry with said opening, means sealing said one end to said hull, said tower being extensible from a folded collapsed condition outwardly from said hull, and a cover operatively mounted on said hull and engageable with said opening to close the same, said tower being foldable and collapsible to a position within said opening and beneath said cover when the latter is closed, said hull in the region immediately beneath said tower being open for occupancy by an operator, said tower being disposed outside said region in both collapsed and extended conditions.
